GEORGE A. LLOYD AND SAMUEL TETLOW, OF SAN FRANCISCO, CALIFORNIA.

Letters Patent No. 69,453, dated October 1, 1867.

IMPROVEMENT IN SEWING-NEEDLES.

The Schedule referred to in these Letters Patent and making part of the same.

TO ALL WHOM IT MAY CONCERN:

Be it known that we, GEORGE ALBERT LLOYD and SAMUEL TETLOW, of San Francisco city and county, State of California, have invented certain new and useful Improvements in "Sewing-Needles;" and we do hereby declare the following description and accompanying drawings are sufficient to enable any person skilled in the art or science to which it most nearly appertains to make and use our said invention or improvements without further invention or experiment.

Prior to our invention hand-sewing needles were made just long enough behind the eye to give sufficient strength to draw the thread through the cloth sewed, and in order to get the bight of the thread through the cloth the needle was forced in by the thimble, a little past the middle, and then seized by the thumb and finger and drawn through. In sewing thick strong cloth, it was often difficult to draw the bight of the thread through the cloth, often requiring the second or third effort before it was accomplished. As it is far easier to exert three or four times the power on a needle, with the thimble or palm to push it through the cloth, than can be readily exerted by the thumb and finger to draw it through, we conceived the idea of making the needle long enough behind the eye to push the bight of the thread through the cloth by the thimble or palm, and thus relieve the fingers from the labor of pulling the bight of the thread through the cloth, and rendering the sewing of thick stiff cloth far easier than heretofore.

Hence the nature of our invention and improvement in hand-sewing needles consists in making the eye so far from the rear end of the shaft of the needle that it will carry the bight of the thread or twine through the cloth sewed, when the needle is pushed by the palm or thimble, and save the drawing of the bight of the thread through with the fingers; also in diminishing the shaft of the needle from a little behind the eye to the rear end, both in width and thickness, so that it may be pulled through easily after being pushed in by the thimble or palm. In the accompanying drawings—

Figure 1 is an elevation of our improved needle.

Figure 2 is an elevation at a right angle to fig. 1, the upper part being shown in section.

In these drawings A is the shaft of the needle, which may be made round or triangular toward the point to adapt it to the kind of work to be sewed. b is the eye of the needle, made from five-eighths to one inch from the rear end of the needle, in common sail-needles, so that the bight of the twine in the eye of the needle can be pushed through the sail-cloth by the palm instead of being pulled through with the fingers. We make a groove, a, on each side of the needle, from the eye to the rear end, for the twine to lie in; and we diminish the shaft of the needle from a little behind the eye gradually to the rear end, both in width and thickness, so that it may be pulled through easily after being pushed in by the thimble or palm. Our improvements in needles will render the sewing of sail and other thick cloth far easier than heretofore by the needles in common use.

Having described our improvements in needles for hand sewing, we claim—

Making the eye so far from the rear end of the shaft that it will carry the bight of the thread or twine through the cloth sewed, when the needle is pushed through the cloth by the thimble or palm, substantially as described.

We also claim diminishing the shaft of the needle from a little behind the eye gradually to the rear end, both in width and thickness, substantially as described.

G. A. LLOYD. [L. S.]
SAMUEL TETLOW. [L. S.]
